(57) **CLAIM**

The ornamental design for a jewelry hangtag, as shown and described.

DESCRIPTION

FIG. 1 is a front perspective view of a jewelry hangtag according to the present invention, the jewelry hangtag holding a necklace shown in broken lines;

FIG. 2 is a front perspective view of the jewelry hangtag of FIG. 1;

FIG. 3 is a front view of the jewelry hangtag of FIG. 1;
FIG. 4 is a rear view of the jewelry hangtag of FIG. 1;
FIG. 5 is a front view of the jewelry hangtag of FIG. 1, the jewelry hangtag holding a necklace shown in broken lines; and,

FIG. 6 is a rear view of the jewelry hangtag of FIG. 1, the jewelry hangtag holding a necklace shown in broken lines. In the drawings, the features shown in broken lines form no part of the claimed design.
